UPHOLSTERY CONSTRUCTION

Albert M. Bank, Jersey City, N. J., assignor to
Sylvia Bank, Jersey City, N. J.

Application June 19, 1935, Serial No. 27,294

9 Claims. (Cl. 155—179)

This invention relates to upholstery construction. It is particularly directed to spring seats or backs for chairs, sofas and the like articles of furniture.

5 An object of this invention is to provide upholstery construction of the character described, having highly improved devices for supporting the foundation springs.

A further object of this invention is to provide 10 compact, strong and durable upholstery construction of the character described, which shall comprise few and simple parts, be easy to incorporate into furniture, relatively inexpensive to manufacture, and yet practical and efficient to 15 a high degree in use.

Other objects of this invention will in part be obvious and in part hereinafter pointed out.

The invention accordingly consists in the features of construction, combinations of elements, 20 and arrangement of parts which will be exemplified in the construction hereinafter described, and of which the scope of application will be indicated in the following claims.

In the accompanying drawing, in which is 25 shown one of the various possible illustrative embodiments of this invention,

Fig. 1 is a top plan view of a chair provided with upholstery construction embodying the invention;

30 Fig. 2 is a cross-sectional, elevational view of the chair shown in Fig. 1;

Fig. 3 is an enlarged cross-sectional view taken on line 3—3 of Fig. 2, with parts broken away; and

35 Fig. 4 is a partial elevational view of a seat illustrating a modified form of the invention.

Referring now in detail to the drawing, 10 designates an article of furniture, such as a chair, provided with upholstery construction embody- 40 ing the invention.

The chair 10 has legs 11 supporting a frame 12 having a front wall 13, a rear wall 14 and side walls 15. Attached to the underside of said front and rear walls 13 and 14 of the frame are 45 a plurality of straps 16, preferably substantially parallel to one another. Said straps 16 may be made of flat elongated sheet metal stock. The front ends 17 of said straps contact and are screwed or nailed directly to the under edge of 50 front wall 13 of the frame. The rear ends 18 thereof contact and are screwed or nailed to the under edge of rear wall 14 of said frame. Adjacent the rear end of each strap 16, is a transversely corrugated or longitudinally sinuous 55 shaped portion 20. Each strap 16 has adjacent

the front end 17 thereof, an upstanding, longitudinally extending, apertured ear 23, preferably stamped from the body thereof and bent upwardly. Each strap, furthermore, has a plurality of spaced longitudinal slots 16a for the purpose 5 hereinafter appearing.

Attached to the upper end of the front wall 13 of the frame, are a plurality of angular brackets 25 vertically aligned with straps 16, each having a horizontal arm 26 contacting the upper edge of 10 said wall, and a vertical arm 26a contacting the inner surface of said wall. Nails, screws or the like fastening devices 27 passing through apertures in said arms, serve to attach the brackets 25 to said front wall. Joining the arms 26, 26a 15 of each bracket, is a loop or ear 28. Interconnecting the ear 23 of each strap to the corresponding bracket 25 is a coil tension spring 29 having a hook at one end engaging said ear, and a hook at the other end engaging the loop 28 of 20 said bracket.

Fixed to the upper edge of rear wall 14 are a plurality of brackets 32, similar to brackets 25, and likewise aligned with straps 16. Said brackets 32 have arms 33 contacting and nailed or 25 screwed to the upper edge of rear wall 14, and arms 34 contacting and fastened to the inner surface of said rear wall. The arms 33, 34 of each bracket 32 are joined by a loop or ear 35.

Received on the corrugated portion 20 of each 30 strap 16 is link 37 having a bottom portion 38 engaging within a channel of said corrugated portion, and a portion 39 having a central upwardly extending humped offset 40. Interconnecting each link 37 with its corresponding 35 bracket 32 is a coil tension spring 42 having a hook at the upper end received in ear 35 of said bracket, and a hook at the lower end engaging the offset 40 of said link. The links 37 may be shifted to engage any part of the corrugated portions 20 of straps 16.

The springs 29 and 42 resiliently support the straps 16. The members 16 are of resilient sheet metal and by reason of the resilient portions 20, 45 serve to resiliently support the foundation springs 44 mounted on said members.

The straps 16 may flex due to the arched shape thereof, as shown in Fig. 2 of the drawing, and also because of the transverse corrugations of 50 portions 20 thereof. The longitudinal length of each strap between the points of attachment thereof is greater than the straight line distance between said points of attachment and since the straps are made of material which can flex, the 55

straps will flex when weight is imposed on the foundation springs 44.

The foundation springs 44 are preferably frusto-conical in shape, increasing in diameter gradually from bottom to top. Extending from the lowermost convolution 45 of each spring 44 is a horizontal diametric end portion 46 extending longitudinally of and contacting strap 16, and having a downwardly offset looped portion bent 10 at right angles thereto and received in one of the slots 16a. The springs 44 thus rest on the straps and are held against shifting thereon. The upper ends of said springs are attached by the tie cords 47 to brackets 25, 32 and to the side walls 15 15 of the frame.

For the purpose of illustration, the drawing shows the invention embodied in a chair seat, but it will be understood that the invention may be incorporated into the usual frame of a chair or 20 sofa back as well as the seat thereof.

In Fig. 4, there is illustrated, a spring edge seat construction including the frame 12 and straps 16b similar to straps 16 and similarly attached to the frame except that the ears 23 are 25 omitted. Mounted on said straps are foundation springs 44a of greater diameter at the ends and gradually decreasing in diameter toward the middle. The springs 44a adjacent the front wall of the frame are close to said wall, the coil 30 springs 29 at the front of the frame being omitted, and said straps being resiliently supported by the rear springs 42 only.

It will thus be seen that there is provided a device in which the several objects of this 35 invention are achieved, and which is well adapted to meet the conditions of practical use.

As various possible embodiments might be made of the above invention, and as various changes might be made in the embodiments 40 above set forth, it is to be understood that all matter herein set forth or shown in the accompanying drawing is to be interpreted as illustrative and not in a limiting sense.

Having thus described my invention, I claim 45 as new and desire to secure by Letters Patent:

1. In upholstery construction, a frame, a plurality of strap members attached at the ends thereof to opposite walls of said frame, each strap having an integral transversely corrugated 50 portion, foundation springs mounted on said strap members, and coil tension springs attached to the frame and to said strap members, inwardly of the ends of the latter.

2. In upholstery construction, a frame, having front, rear and side walls, a plurality of 55 substantially parallel strap members attached to the front and rear walls, each member having, adjacent the rear ends thereof, an integral transversely corrugated portion, a connecting member on each corrugated portion, coil tension springs each having one end engaging a connecting member and the other end connected to the rear wall of said frame, and foundation springs mounted on each strap member.

3. In upholstery construction, a frame, having front, rear and side walls, a plurality of substantially parallel strap members attached to the front and rear walls, each member having, adjacent the rear end thereof, an integral transversely corrugated portion, a connecting member on each corrugated portion, coil tension springs each having one end engaging a connecting member and the other end connected to the rear wall of said frame, foundation springs 70 mounted on each strap member, said strap mem-

bers having apertured upturned ears adjacent the front ends thereof, and coil tension springs interconnecting said ears with the front wall of said frame.

4. In upholstery construction, a frame, a plurality of strap members attached at the ends thereof to opposite walls of said frame, each strap having an integral transversely corrugated portion, foundation springs mounted on said strap members, each of said strap members being provided with upstanding fastening members and a coil tension spring interconnecting said fastening member with a wall of said frame.

5. In upholstery construction, a frame having a front wall and a rear wall, a plurality of strap members attached at the opposite ends thereof to said front and rear walls, said straps being made of flat, elongated strips of sheet metal, and each having a longitudinally sinuous portion adjacent one end and a plurality of spaced slots, inverted conical foundation springs on said straps, said springs having at the bottom thereof, portions projecting into said slots, and a resilient connection between said sinuous portion of each strap and said rear wall.

6. In upholstery construction, a frame, a plurality of strap members attached at the ends thereof to opposite walls of said frame, said straps being made of flat, elongated strips of sheet metal, each having a longitudinally sinuous 30 portion adjacent one end and a plurality of spaced slots, inverted conical foundation springs on said straps, said springs having at the bottom thereof, portions projecting into said slots, and a coil tension spring interconnecting the sinuous 35 portion of each strap with one wall of said frame.

7. In upholstery construction, a frame, a plurality of strap members attached at the ends thereto to opposite walls of said frame, said straps being made of flat, elongated strips of sheet metal, each having a longitudinally sinuous portion adjacent one end and a plurality of spaced slots, inverted conical foundation springs on said straps, said springs having at the bottom thereof, portions projecting into said slots, 40 a coil tension spring interconnecting the sinuous portion of each strap with one wall of said frame, and a coil tension spring interconnecting a portion of each strap adjacent the opposite wall of the frame with the latter.

8. In upholstery construction, a frame having a pair of parallel upstanding opposite walls, a flexible strap member interconnecting the bottom portions of said walls, foundation springs supported by said strap member, and a coil tension spring interconnecting the upper edge of each of said walls with a portion of said strap spaced from said wall, whereby an upward yielding pull is exerted on said strap member to aid in supporting said foundation springs.

9. In upholstery construction, a frame having a pair of upstanding opposite walls, a flexible strap member interconnecting portions of said walls, said strap member being greater in length between the points of attachment thereof with said walls than the straight line distance between said points of attachment, foundation springs supported by said strap member, and a pair of coil tension springs interconnecting spaced intermediate portions of said strap member with said walls, the points of attachment of said springs to said walls being above the points of attachment of the adjacent ends of said strap member to said walls respectively.

ALBERT M. BANK.
